PLASTIC POWDER BOX

John Schwarz, Glendale, Calif.

Application July 2, 1956, Serial No. 42,119

Term of patent 14 years

(Cl. D86—10)

Fig. 1

Fig. 3

Fig. 2

Figure 1 is a perspective of the plastic powder box embodying my new design, with its lid in closed position,

Figure 2 is a perspective of the powder box with its lid in open position, the powder puff indicated in dotted lines being shown for illustration purposes only,

Figure 3 is a cross section through the lid of the powder box.

I claim:

The ornamental design for a plastic powder box, substantially as shown, and described.
